UNITED STATES PATENT OFFICE.

EDWARD HOLLINGWORTH, OF DOBCROSS, ENGLAND, ASSIGNOR TO CROMPTON & KNOWLES LOOM WORKS, OF WORCESTER, MASSACHUSETTS, A CORPORATION OF MASSACHUSETTS.

SHEDDING MECHANISM FOR LOOMS FOR WEAVING.

Application filed June 14, 1927, Serial No. 198,831, and in Great Britain June 16, 1926.

The invention relates to loom shedding mechanism of the tappet and treadle type, and has for its object to provide an improved construction or arrangement of mechanism of 5 this type which will be especially suitable for use in looms for weaving heavy fabrics, such for instance as carpet looms.

In the arrangement most commonly employed in such looms a series of cams are secured on a sleeve mounted loosely on the bottom shaft of the loom, and are driven by means of a gear wheel fast on the sleeve and meshing with a pinion on the loom crank shaft, the treadles or jacks being disposed above the 10 tappets. This arrangement is found in practice to possess certain disadvantages which it is the object of the present invention to overcome or remove.

According to the invention, the tappets are 20 mounted on a short shaft disposed parallel with the crank shaft at a suitable distance in rear of the line of same and at, or substantially at, the same vertical level. A pinion fast on the crank shaft meshes with a pinion on a 25 counter shaft disposed in front of the line of the crank shaft, and another pinion on this counter shaft meshes with a gear wheel of appropriate ratio fast with the tappets. The tappet levers are disposed beneath the tappets, 30 being mounted pivotally at their rear ends on a shaft at the rear of the loom.

The counter shaft, the shaft on which the tappets are mounted and the shaft on which the tappet levers are mounted, are all journaled at their inner ends in the side frame of 35 the loom and at their outer ends in an auxiliary frame suitably spaced from the side frame.

The front ends of each adjacent pair of tappet levers are each connected by a chain to a 40 pulley or drum mounted to rotate freely on a shaft journaled between the loom side and the auxiliary frame, the chain from one lever passing around the pulley in one direction 45 and that from the other lever in the opposite direction, so that as one lever is depressed by its bowl to raise its heald, the other lever is correspondingly raised to draw down its heald.

50 In the accompanying drawings,

Fig. 1 is a front view of shedding mechanism, according to the invention, arranged for operating three healds, which may control, say, two binder warps and a stuffer warp

in a loom for producing Wilton, Brussels, or 55 other form of carpet.

Fig. 2 is a partial plan view, and

Fig. 3 a partial sectional end elevation, looking in the direction of the arrow 3, Figure 2.

60 Referring to the drawings, *a*, *a* represent the healds or harnesses each connected to respective upper and lower shedding levers *b* and *b'*. The crank shaft of the loom is represented at *c*, and the left hand end frame at *d*. For the purposes of the invention an auxiliary end frame *e* is provided, spaced from the end frame *d* by stretchers *f*, *f*.

The tappet shaft is shown at *g*, journaled at its inner end in the loom frame *d* and at its 70 outer end in the auxiliary frame *e*. This shaft *g* is, as shown, disposed parallel with the crank shaft *c* and in rear of same at substantially the same vertical level. Also journaled between the frames *d* and *e*, in 75 front of the crank shaft and also at substantially the same level as the crank shaft is a counter shaft *h* carrying a pinion *i*, with which a pinion *j* on the crank shaft meshes. A second pinion *k* on the counter shaft *h* so meshes with a gear *m* on the tappet shaft. The tappets *n'*, *n*, for operating two of the healds, say those controlling the two binder warps, are formed on one block *n*³, and the tappet *o* for operating the third heald for the 85 stuffer warp, is formed on a second block *o'* along with a fourth tappet *o*² which, in the instance shown, is a dummy tappet, but serves a purpose mentioned later. The two tappet blocks *n*³ and *o'* are mounted on a boss *m'* fast 90 with the gear *m*, and the said blocks are rigidly secured to the gear *m* by bolts *p*. By forming adjacent pairs of tappets integral on one block or hub, they can be set or formed to so act upon their respective levers as to 95 cause the correct movements of a connected pair of healds, and can retain this correct setting without possibility of displacement such as might occur under heavy strain if the tappets were separately secured. The pair of 100 tappets on each block are set diametrically opposite to one another.

The tappet levers, *r'*, *r*², *r*³ and *r*⁴, are disposed as shown beneath the tappets and are pivoted at their rear ends on a shaft *s* extending between the end frame *d* and a bracket *e'* secured to the auxiliary frame *e*.

105 Each of the tappet levers *r'*, *r*² and *r*³ is

connected towards its front end, by a vertical connector t' , t^2 or t^3 , adjustable as to length, to its respective upper shedding lever, and by another connector u' , u^2 or u^3 , also adjustable as to length with the respective lower shedding lever.

The front ends of the pair of tappet levers r' and r^2 are each connected by a respective chain v' or v^2 to a pulley or drum v^3 rotatable 10 freely on a shaft v^4 extending between the frames d and e , the chain v' being carried around the pulley in one direction, and the chain v^2 in the opposite direction. It follows, therefore, that as one of the pair of tappet 15 levers is depressed to raise its heald, the other lever of the pair is correspondingly raised to draw down its heald. In similar manner the third tappet lever r^3 is connected by a chain w' to a pulley or drum w^2 , also loose on the 20 shaft v^4 , and another chain w^3 fast to the drum w^2 but passing about it in the opposite direction to the chain w' is connected to a tappet lever r^4 adapted to be operated by the dummy tappet o^2 . This tappet o^2 thus operates to balance the third or odd heald operated by the tappet o and tappet lever r^3 , and to draw down the said heald.

Each tappet lever is provided with a bowl z disposed in a central slot or recess z' in the 30 lever and mounted to rotate freely on a transverse pin z^2 extending across the slot. The bowls are, as shown, of relatively large diameter, and the levers are so shaped that their pivot centres, the centres of the bowls, the 35 points of connection to the healds, and the points of connection to the balancing chains, all lie in the same plane.

The tappets, being in the form of open cams working in the same plane as the bowls

they engage, exert a direct central pressure 40 on the tappet levers, and this permits of the use of tappets and bowls of relatively large width which, combined with the permissible use of large diameter bowls enables the parts to be of great strength and conduces to ease 45 in working. The bowls may, if desired, be mounted on ball or roller bearings to minimize friction.

The arrangement of the mechanism described eliminates necessity for off-setting or 50 cranking of the tappet levers employed, and this again adds to the strength.

Having thus described my invention, what I claim as new and desire to secure by Letters Patent is:—

Loom shedding mechanism comprising harnesses, upper and lower shedding levers for each harness, a crankshaft, a cam shaft positioned at the rear of and substantially on the level with said crankshaft, a speed 60 reducing gear connection between said shafts, a plurality of external cams mounted in reverse pairs on said cam shaft, tappet levers mounted in pairs, extending transversely below said shafts and cams and each engaged 65 and actuated in one direction only by one of said cams, connections from each tappet lever to the upper and lower shedding levers of one of said harnesses, and cross connections between the two tappet levers operated by a 70 pair of adjacent reversed cams whereby one lever is raised as the other is depressed by its associated cam, each cam of each pair alternately moving two harnesses simultaneously in opposite directions.

In testimony whereof I affix my signature.

EDWARD HOLLINGWORTH.
